UNITED STATES PATENT OFFICE.

KIICHIRO TOYODA, OF NAGOYA, JAPAN.

SHUTTLE-CHANGING APPARATUS FOR AUTOMATIC LOOMS.

Application filed August 23, 1926. Serial No. 130,907.

My invention relates to a shuttle changing apparatus adapted for use in any automatic loom.

In the hitherto known apparatus, there are disadvantages in that the shuttle ejected from the magazine must be forced against a considerable resistance and that the shuttle is liable to be injured by the shock and friction on engaging the inclined guide face on the front plate of the shuttle box. The object of the present invention is to overcome these disadvantages by the provision of the front plate adapted to be opened not by the engagement of the shuttle but by a separate means before coming into engagement with the shuttle, resulting in a soft operation.

Another object of the invention is the provision of the means whereby the picker is displaced away from the shuttle when the latter is to be changed, thus preventing the injury of the shuttle while being removed.

In the accompanying drawings in which one embodiment of the invention is shown by way of example:

Figure 1 is a side view of the apparatus, Figure 2 a front view, and Figure 3 a plan thereof.

On the slay 1 is mounted a bearing bracket 2. The front plate 3 of the shuttle box is carried by the arm 4 which is pivoted on the pivot 5 in the bracket 2. A rocking extension arm 6 is secured to the arm 4 by means of bolts 7.

8 is the shuttle magazine securely mounted on the loom frame. Properly guided in the frame, a shuttle ejecting rod 9 is provided for ejecting the lowermost one of the shuttles in the magazine 8. The ejecting rod 9 is connected by a link 10 to the upper arm 11 fixed to a horizontal shaft 12 journaled in the frame. To the shaft 12 is also fixed a lower arm 13, to which is connected a receiving rod 14. By means of the hanging rod 15 and by other connecting means, the said receiving rod 14 is operatively connected to the feeler motion device in such a manner that it is slightly lifted when the weft is broken or exhausted, whereupon it is actuated by an engaging member (not shown) formed or secured on the slay sword. Also secured to the shaft 12 is an operating arm 16.

When the shuttle is to be changed, the receiving rod 14 is actuated by the engaging member on the slay 1, whereby the lower arm 13 is rocked about the axis of the shaft

13, thus operating the ejecting rod 9 through the upper arm 11 and the link 10, resulting in the lowermost one of the shuttles in the magazine 8 being ejected and propelled toward the shuttle box. At the same time the operating arm 16 on the shaft 12 will be rocked downwardly, so that according to the forward stroke of the slay the extension arm 6 will be engaged and pushed by the operating arm 16. Consequently, the front plate 3 of the shuttle box will be opened, the arm 4 thereof being rocked about the pivot 5. Thus, it will be seen that the front plate 3 will be opened before it is engaged by the shuttle ejected from the shuttle box, and consequently, the ejected shuttle can be safely pushed into the shuttle box without any resistance.

Mounted on the slay front is a bearing 17 in which a vertical operating shaft 18 is journaled, which shaft carrying at its upper end an operating arm 19, and at the lower two members 20 and 21. The outer member 21 is bent and abuts against the tail of the check strap 22 for the picking arm. The operating arm 19 and the members 20 and 21 are normally held in the position shown in Figure 3 by the action of the springs 23 and 24. Thus, the check strap 22 for the picking arm is normally prevented from moving outwardly beyond the predetermined extent, the same being checked by the bent portion of the outer member 21.

During the shuttle changing operation, the extension arm 6, being moved by the operating arm 16, will engage with and actuate the operating arm 19 on the shaft 18, so that the inner and outer members 20 and 21 fixed at the lower end will be rocked outwardly. Thus, the outer member 21 will release the check strap 22, permitting the latter to be moved outwardly beyond the normal extent. At the same time, the inner member 20 will push the picking arm 25 outwardly, moving the picker in the direction of the arrow shown in Figure 3, thereby making a gap between the shuttle and the picker, and thus permitting the removal of the shuttle without any hindrance.

Nearly at the end of the forward stroke of the slay, that is, when the shuttle ejected from the magazine passes the entrance of the shuttle box, the operating arm 16 will be moved into the position shown in broken lines, and will become disengaged from the extension arm 6, whereupon the latter arm

6 will be returned to its normal position by the action of the spring 26, closing the front plate 3 of the shuttle box. Consequently, the operating arm 19 being released from the extension arm 6, both members 20 and 21 will also be returned to their normal position by the action of the springs 23 and 24, the bent portion of the outer member 21 again holding the tail of the check strap 22 for the picking arm.

In the hitherto known device for changing shuttles in automatic looms, the front plate of the shuttle box is provided with an inclined guide face, and the ejected shuttle is forced against this guide face for opening the front plate. So, there are disadvantages that the ejected shuttle must be forced against a considerable resistance and that the shuttle is liable to be injured by the shock and friction caused by the engagement with the front plate of the shuttle box. These disadvantages may be removed by the present invention, in which as described above the front plate 3 of the shuttle box is opened before it is engaged by the ejected shuttle. Thus, it may be observed that according to this invention the guide face at the entrance of the shuttle box may be dispensed with, and yet the shuttle may be readily fed into the shuttle box without injuring the same.

In the automatic loom hitherto known, there is also a disadvantage that during the shuttle changing operation the removal of the shuttle is hindered by the fact that the tip of the shuttle is held engaged by the receiving cavity in the picker, and consequently that the shuttle is liable to be injured by the forcible push of the same when it is re-

moved. In this invention, however, such disadvantage may be overcome by displacing the picker outwardly during the shuttle changing operation, thereby releasing the shuttle to be readily removed.

What I claim is:—

1. In an automatic loom, the combination of the slay, the shuttle magazine, a shuttle-box having a movable front-wall, a shuttle ejecting means, a picker, a check therefor, a pivoted arm carrying said movable front-wall, a spring-controlled extension secured to said arm, a horizontal rock-shaft, means carried thereby for simultaneously operating said shuttle ejecting means and said pivoted arm, a vertical rock-shaft adapted to be rocked by said extension, means on said vertical rock-shaft for releasing said picker, and means on said vertical rock-shaft for moving said picker out of the path of the fresh shuttle.

2. In an automatic loom, the combination of the slay, the shuttle magazine, the shuttle-box having a movable front-wall, a shuttle ejecting means, a picker, a check therefor, a pivoted arm carrying said movable front-wall, a spring-controlled extension secured to said pivoted arm, a horizontal rock-shaft, means carried thereby for simultaneously operating said shuttle ejecting means and said pivoted arm, a vertical rock-shaft, an arm mounted thereon and adapted to be engaged by said extension, a member carried by said vertical rock-shaft for releasing said picker, and a second member on said vertical rock-shaft for moving said picker out of the path of the fresh shuttle.

In testimony whereof I affix my signature.
KIICHIRO TOYODA.
